H. HURM

VIBRATING DEVICE

Filed March 25, 1922

Inventor
Horace Hurm

By *James L. Ross*,
Attorney

UNITED STATES PATENT OFFICE.

HORACE HURM, OF PARIS, FRANCE.

VIBRATING DEVICE.

Application filed March 25, 1922. Serial No. 546,930.

To all whom it may concern:

Be it known that I, HORACE HURM, citizen of the French Republic, residing at Paris, France, have invented certain new and useful Improvements in Vibrating Devices, of which the following is a specification.

This invention relates to vibrating devices provided with tension springs and refers more particularly, although not exclusively, 10 to sound boxes for phonographs provided with such springs, as it is in the case of these sound boxes that the improvements forming the subject of the invention appear to be of the greatest importance.

15 The chief object of the invention is so to construct devices of this character that they function more satisfactorily than has hitherto been the case.

The invention consists essentially in providing, as the spring member of such a device, a simple wire so formed and arranged and made from such material that, when suitably stretched, it possesses the required elasticity.

20 In addition to the principal feature just mentioned, the invention includes various details, which are preferably utilized at the same time and which will be more fully described hereafter.

25 It also relates to a special constructional embodiment, in which the invention is applied to the sound box of a phonograph and it includes, as new industrial products, devices of the character mentioned embodying 35 the said improvements, and special parts suitable for their construction.

In order that the invention may be clearly understood, it will now be described with reference to the accompanying drawing, but 40 it is to be pointed out that the description and drawing are given merely by way of example.

Figs. 1 and 2 of the said drawing, show respectively, in front elevation and in axial 45 section, a sound box for a phonograph embodying the invention.

Fig. 3 is a plan view of the tensioning or loop member and associated parts.

Figs. 4, 5 and 6 are sections on an enlarged scale on the lines 4—4 Fig. 1, 5—5, 50 Fig. 2 and 6—6, Fig. 2, respectively, illustrating certain parts utilized in the construction of the sound box.

The invention is shown as applied to a sound box of the kind having a stylus bar *d* shaped as a struttured beam. The stylus bar

is provided adjacent its outer end *d*¹ with a small transverse member *d*², in which are formed symmetrically placed shallow depressions at equal distances on each side of the central plane of the device. These depressions are so arranged that they enable the stylus bar to be pivotally mounted upon the casing *b*, which casing carries the vibrating diaphragm *a*. For the purpose of this pivotal mounting, two small screws *f* are employed, screwing through small pillars *g* carried by the outer face of the box *b*. *d*³ is a hook and *j* is a connection for holding the stylus bar upon its pivots and for pressing the inner end thereof upon the diaphragm *a*. This connecting member *j* connects the hook *d*³ and a pillar *k*, which pillar projects from the face of the casing diametrically opposite a point midway between the pillars *g*, and, in the usual construction, a spring is provided for attaching the member *j* to the column *k*.

The portions of the device, other than those already mentioned for holding the stylus bar *d* in pivotal connection upon the box *b* and for enabling it to exercise an elastic pressure upon the central portion of the diaphragm *a*, may be of any suitable construction.

80 The transverse members *d*², contrary to what has been the practice hitherto, is preferably made from the same material as the stylus bar itself. It may, with advantage, be made from duralumin as has usually 85 been the case with the stylus bar, and it may be riveted thereto.

The shallow depressions formed in the transverse member *d*², may also, in place of coming directly upon the ends of the screws, 90 as has been usual hitherto, have small pads, preferably of fibre, contained therein, upon which the points of the screws bear. These portions of the construction are preferably such as shown clearly at Figs. 1, 2 and 6. 100

Instead of making the connecting member *j* of a cord and spring connection, as has previously been the case, I now propose to make the same from a stretched thread, preferably a metal wire, which, when properly stretched, gives the required elasticity.

Instead of connecting the member *j* to the pillar *k* on the casing by means of a spring, as has been previously proposed, I provide a rigid device for effecting the attachment.

According to my present invention, I

form the connecting member and the rigid device as follows:

I take a length of steel wire, such as piano wire, say of 1.5 tenths of a millimeter in diameter, or I may take hardened silver wire, say of two tenths of a millimeter in diameter. This is bent back upon itself or into the shape of a U to extend over the hook d^3 as will be clearly seen. I also provide a small bar or block j^1 which is furnished with two perforations, through which the free extremities of the wire j can be threaded.

The bar or block j^1 is also formed with screw threaded holes extending substantially at a right angle to and transversely of the first mentioned holes, to receive locking screws j^2 , the construction being such that the ends of these screws push the inserted wires into bottoms of the holes and retain them firmly in position within the said holes.

I attach to the block or bar j^1 one extremity of a screw threaded rod j^3 . This rod has a groove extending along its length corresponding with one position of its generating line.

In some cases, contrary to what is shown upon the drawing, the rod j^3 may have its axis parallel to the axes of the holes or conduits through which the wires pass. I prefer, however, to connect the rod j^3 to the block j^1 as shown in the drawing so that the axis of the rod is perpendicular to the plane passing through the axes of the holes. In this way, when the extremities of the wires have been placed in position, the loop is turned over so that the said loop and the rod extend in parallel directions on opposite side of the bar or block. The groove formed on the surface of the bar is also turned into such a position that it corresponds to the position of the generating line nearest to the parts of the wire j .

The pillar k is provided with a plain hole through which the rod can slide freely. It is also provided with a screw threaded hole at substantially a right angle to the axis of the first mentioned hole, and a locking screw k^1 screws into the last mentioned hole. In this way when the rod j^3 has been placed in position and the screw k^1 is screwed in to enter the groove in the rod, the rod is prevented from rotating but is free to slide longitudinally.

j^4 is a nut adapted to screw on to the end of the rod j^3 and to bear against the pillar k or against an interposed washer. In this way a pull can be exerted upon the rod j^3 and consequently upon the wire loop j , which latter can be stretched to any required degree.

In this way, when all the parts are accurately fitted and arranged by suitable turning the nut j^4 , a sound box is obtained capable of delicate regulation and giving the finest results. Moreover, owing to the man-

ner in which the resilient member is made it eliminates the greater part of the secondary vibrations.

In some cases I provide pads j^0 upon the wire j . These pads are of buffering or deadening material from the acoustical point of view, for instance of rubber. They more completely eliminate secondary vibrations and prevent all risk of contact between the wires and the stylus bar d , and to a certain extent clamp this latter laterally, so that it is prevented from vibrating laterally, while being left free to vibrate in its own plane of symmetry, the said pads in the latter case functioning as rollers, which turn upon their own axes under the action of the friction exerted upon them by the side faces of the stylus bar.

As will be clearly understood and as has already been remarked, the invention is not limited in any way to those methods of construction or to those details which have been particularly described, but includes all modifications coming within a fair interpretation of my claims.

What I claim as my invention and desire to secure by Letters Patent in the United States of America is:—

1. In a tensioning means for vibrating devices of the class specified, the combination with a box enclosure and a diaphragm therein, of a pivotally mounted stylus in the form of a beam having a hook at the outer extremity and an inner point engaging the center of the diaphragm, of a cross member secured to the beam and pivotally connected to the box enclosure, an adjusting bar also carried by a portion of the box enclosure, and a looped wire engaging the hook of the stylus beam and connected to the said adjusting bar.

2. In a device of the class specified, the combination with a box enclosure having a diaphragm mounted therein and a pivotally mounted stylus bar provided with an inner diaphragm-engaging extremity, of a wire loop engaging an outer portion of the stylus bar, and adjusting means secured to a portion of the box enclosure and comprising an adjusting bar to which the wire loop is attached and having a screw-threaded rod for varying the tension of the wire loop to modify operative association of the inner extremity of the stylus bar relatively to the diaphragm.

3. In a sound box for a gramophone of the type described, the combination with a box enclosure having a diaphragm therein and a stylus bar having pivotal connection with the edge of the box enclosure and having an inner extremity movably engaging the center of the diaphragm, of an adjusting means connected to the edge portion of the box enclosure and comprising a longitudinally movable screw rod and an

adjusting bar carried by said rod, and a wire loop applied around a portion of the outer extremity of the stylus bar and having its ends secured in the said adjusting bar.

4. In a sound box for a gramophone of the type described, the combination with a box enclosure having a diaphragm therein, a stylus bar pivotally connected to the edge portion of the box enclosure and having its inner extremity movably engaging the diaphragm, a column secured to the edge portion of the box enclosure diametrically opposite said pivotal connection and having a screw-threaded rod shiftably mounted therein, the screw-threaded rod being provided with an adjusting cross bar, a wire loop engaging a portion of the outer extremity of the stylus bar and having the

ends thereof removably secured in the adjusting bar, and a nut engaging the screw rod.

5. In a sound box for a gramophone of the class specified, the combination with a box enclosure having a diaphragm mounted therein, of a stylus bar having a cross member adjacent its outer extremity pivotally connected to the adjacent edge portion of the box enclosure and also provided with a hook, a wire loop engaging the hook at the outer extremity of the stylus bar, and an adjusting bar operatively associated with an opposite edge portion of the box enclosure and having the ends of the wire loop secured therein.

In testimony whereof I have hereunto set my hand.

HORACE HURM.
